UNITED STATES PATENT OFFICE.

RUDOLF HORN, OF DRESDEN, GERMANY.

PRINTING PRESS.

Application filed October 28, 1924, Serial No. 746,270 and in Germany October 31, 1923.

The present invention relates to that class of printing-presses (off-set press) in which, for the production of impressions or prints on paper, webs, sheet-metal plates or the like, 5 at least and without any exception, one cylinder carrying zinc-plates or forms carrying the original or printing picture and one cylinder stretched with rubber are arranged. The cylinder carrying or stretched with zinc- 10 plates or blankets operates together with the rubber cylinder and transfers the inked original or printing picture to the rubber cylinder mentioned, from which it is hereafter printed onto the paper, web or the sheet-metal plates.

The present invention has for its object to fully dispense with the cylinder carrying the zinc-plates and to directly transfer the printing picture to the rubber cylinder and to 20 print it from said cylinder onto the paper or other material to be printed. The construction of the printing-press is highly simplified and cheapened by dispensing with the cylinder carrying the zinc-plate. Furthermore 25 the necessary intermediate transfer from zinc to rubber necessary for the printing-presses known up to now is fully dispensed with, whereby a more intensive clearness of the picture is ensured also. Furthermore 30 the working of the printing-press will not only be an easier one by dispensing with said cylinder carrying zinc-plates, but it can even run with a higher printing-speed also.

The object of the present invention is represented in the drawing annexed by way of example in two constructions. Fig. 1 is a 35 rotating rubber printing-press for printing separate sheets, Fig. 2 a press for printing a continuous paper-sheet or band.

40 *a* is the rubber cylinder stretched in a known manner with rubber plates *b*. Instead of rubber, linoleum or other flexible nonmetallic plates may be used. The rubber plates are prepared, for instance by roughening and 45 treating them with acetic acid in such a manner that practice shows they obtain qualities equal to those of the zinc-plates or stones heretofore used for printing purposes, in other words that said plates absorb water and 50 fatty inks. The print-picture is then transferred to the plates prepared in the manner indicated. The wetting-apparatus *c* serves to moisten the so called empty points of the rubber plate on which, therefore, is no print-picture, so that the inking rollers *d* deliver 55 their fatty ink to the printing-picture itself

only, whereas the empty points of the rubber-plate moistened by the wiper-rollers do not allow the ink to adhere. The sheet is applied to the printing cylinder *e* in a known manner, 60 printed by the rubber cylinder and hereafter lifted up to the device *f*. One rubber-plate only or more than two such plates may be arranged on the cylinder *a*.

Fig. 2 represents a rotating rubber printing-press in which, the paper is printed simultaneously on both sides. For this purpose there are two cylinders *a*¹, *a*² provided with rubber plates. These cylinders work together and are provided with one or more proper inking apparatus *d*¹, *d*² and wetting-apparatus *c*¹, *c*². If it is intended to print one surface of the paper only the inking and wetting apparatus of one cylinder are disengaged, so that this cylinder forms the counter cylinder for the second cylinder.

It is preferable to transfer the printing pictures to the rubber-web from the original picture or from the reprint only if the rubber-webs are stretched under tension around the cylinder already. This can be performed for instance by inking in advance the reprint or the original of the printing-picture present for instance on the zinc-plates and then allowing it to run through the rubber printing press like a sheet to be printed. The inked printing picture then prints on the rubber-plates whereby the rubber linings are transformed into printing plates to be wetted and inked.

90 What I claim is:

1. In a rotary printing press for direct lithographic printing, a printing cylinder, an impression cylinder, inking rolls, and a plate of flexible, soft and resilient material on the said printing cylinder, the said printing plate being prepared for direct application thereto of ink from the inking rolls and for printing directly therefrom on a sheet passing between the same and the impression cylinder.

105 2. In a rotary printing press for direct lithographic printing, a printing cylinder, an impression cylinder, inking rolls, damping rolls, and a plate of flexible, soft and resilient material stretched on the said printing cylinder, the said plate of flexible, soft and resilient material being prepared for taking ink directly from the printing rolls and moisture from the damping rolls and printing directly 110 therefrom on a sheet passing between the same and the impression cylinder.

3. In a rotary printing press for direct lithographic printing, a printing cylinder, an impression cylinder, inking rolls, and a plate of flexible, soft and resilient rubber on the 5 said printing cylinder, the said plate of flexible, soft and resilient rubber being prepared for directly receiving ink from the inking rolls and for printing on a sheet passing between the same and the impression cylinder.
- 10 4. In a rotary printing press for direct lithographic printing, a printing cylinder, an impression cylinder, inking rolls, damping

rolls, and a plate of flexible, soft and resilient rubber stretched on the said printing cylinder, the said plate of flexible, soft and resilient rubber being prepared for receiving ink direct from the inking rolls and moisture from the damping rolls and for then printing directly therefrom on a sheet passing between the same and the impression cylinder. 15

In testimony, that I claim the foregoing as my invention, I have signed my name this 8th day of October, 1924.

RUDOLF HORN.
